UNITED STATES PATENT OFFICE.

EMMA BEATRICE BENSON, OF BEVERLY, KANSAS.

SKEIN HOLDER.

Application filed January 11, 1924. Serial No. 685,625.

To all whom it may concern:

Be it known that I, EMMA BEATRICE BENSON, a citizen of the United States, residing at Beverly, in the county of Lincoln and 5 State of Kansas, have invented certain new new and useful Improvements in Skein Holders, of which the following is a specification.

This invention relates to an improvement 10 in skein holders particularly useful to those practicing the embroidery art, the primary object of the invention residing in the provision of a skein holder wherein a plurality of skeins of embroidery material may be placed within the holder and this in spaced 15 relation to each other, whereby the different strands of material forming the skeins are held in tort relation and whereby the different strands of the different skeins may 20 be withdrawn when desired without any liability of tangling the remaining strands of the different skeins.

A still further object of the invention is 25 to provide a holder of the above character wherein skeins are not only maintained as above set forth, but wherein the same are fully protected from any dirt or dust that might arise in the room wherein the embroiderer is working.

30 A still further object resides in the provision of a skein holder wherein the same may be readily rolled into a compact form and stored away when not in use, and this without the necessity of removing the different skeins therefrom.

Yet another object is to provide a skein 35 holder wherein the same may be manufactured and marketed at extremely small cost, the same embodying but a relatively few pieces of material, and these so stitched or correlated as to reduce the possibility of disarrangement of pieces of material to a minimum.

With the above and other objects in view 45 as the nature of the invention will be better understood, the same comprises the novel form of a skein holder hereinafter more fully described, shown in the accompanying drawing and claimed.

50 In the drawing wherein like reference characters indicate corresponding parts throughout the several views,

Figure 1 is a top plan view of a skein

holder constructed in accordance with the present invention,

55 Figure 2 is an enlarged detail, transverse, cross-sectional view thereof, and

Figure 3 is a fragmentary, longitudinal, view taken through one end of the skein 60 holder.

Now having specific reference to the drawing, a skein holder constructed in accordance with the present invention embodies a backing 5 of suitable fabric, the same being of a relatively long and wide 65 nature, the corners of which are, as clearly shown in Figure 1, rounded. Arranged transversely upon opposite ends of said backing strip 5 are relatively narrow strips of similar fabric, 6—6, while arranged intermediate said end strips 6—6 in slightly spaced relation thereto and in spaced relation to each other, are substantially square-shaped strips of material 7—7.

Surrounding the edges of said backing 75 strip 5, is a single length strip of reinforcing material 8 that is stitched to the edges of said backing strip and also serves as a means for securing the horizontal edges of 80 said strips 7—7 to the adjacent edges of 85 said backing strip 5, this reinforcing material also serving as a means when the same is stitched to the edges of the backing material for securing thereto the outer and end edges of said end strips 6—6.

The inner edges of said end strips 6—6 are reinforced in a suitable manner as at 6'—6', it being however noted from a consideration of Figure 3, that said inner edges 90 of these strips 6 are not secured to the backing strip 5, these strips-cooperating with the ends of the backing strip for providing pockets 9 for the reception of the ends of the different skeins of material A.

The opposite ends of the square-shaped 95 strips of material 7—7 are also reinforced as at 11 and for providing longitudinal pockets 12 for the reception of the different skeins of embroidery material, horizontal rows of stitching are extended through said strips 7—7 and the backing 5 throughout the combined length of said strips 7—7. It is preferable that these different rows of 100 stitches be formed from a continuous stitching operation.

105 It will thus be seen that I have provided

a skein holder that includes a plurality of longitudinal pockets for holding a plurality of skeins of material and that complementary to the remote ends of said pockets single pockets are formed for receiving the ends of the different skeins for consequently preventing the same from becoming dirty and the like. It will also be seen that by provision of a skein holder of the present 10 nature, certain strands of different skeins of material may be readily removed from the holder without any liability of tangling the different strands of material.

Numerous advantages of a skein holder 15 of this character will be at once appreciated by those working in the art to which this invention pertains and even though I have herein set forth the most practical embodiment of the invention with which I am at 20 this time familiar, it is nevertheless to be understood that minor changes may be made in the invention without departing from the spirit and scope of the appended claim.

Having thus described my invention, what I claim as new and desire to secure by Letters Patent, is:—

A skein holder of the class described including a strip of flexible material, a piece of flexible material having its edges fixed to the edges of the strip, a second piece of flexible material having its edges fixed to the edges of the strip, means for attaching the pieces to the strip along longitudinal spaced lines for forming compartments, the compartments in between the strip and the first piece being aligned with the respective compartments in between the strip and the second piece, and pockets formed at the ends of the strip and open toward the compartments, the ends of the compartments being open so that skeins may be extended through the compartments and terminate in the pockets.

In testimony whereof I affix my signature.

EMMA BEATRICE BENSON.
